UNITED STATES PATENT OFFICE.

HENRY MARCHETER, OF WALLACEBURG, ONTARIO, CANADA.

SELF-ACTING SAFETY-GATE FOR SWING-BRIDGES.

SPECIFICATION forming part of Letters Patent No. 352,251, dated November 9, 1886.

Application filed February 18, 1886. Serial No. 192,372. (No model.)

To all whom it may concern:

Be it known that I, HENRY MARCHETER, a subject of Her Majesty Queen Victoria, and a resident of Wallaceburg, county of Kent, and 5 Province of Ontario, Dominion of Canada, have invented new and useful Improvements in Safety-Gates for Bridges, of which the following is a specification.

My invention relates to improvements in 10 gates for swing-bridges using weights to pull up the gate, and a lever acted upon by the swing part of the bridge to force the gate down out of the way. I attain these objects by the mechanism illustrated in the accompanying 15 drawings, in which—

Figure 1 is a side view of the approach, showing the gate up in place, the swing part being away at this time. Fig. 2 is a similar 20 view, but shows the gate lowered and out of the way as the swing is returned and rests on the lever, thereby lowering the gate. Fig. 3 shows the iron bearer attached central and underneath and at the end of the swing, and is so adjusted that it will ride upon the end of 25 the lever that projects beyond the end of the approach, and gradually pulls the gate down until at last it rests its maximum bearing and continuously holds the gate down.

Similar letters refer to similar parts throughout the several views.

A is the approach.

B B in the drawings show the uprights of the gate now up in place with F, which is a rod of iron or wood, and forms the top of the 35 gate. The gate can be made of any material or shape most desirable.

C is the weight, I grooved wheel, and D the chain.

E is a sheath to keep the end of the lever in 40 place.

G is the lever, and H the projecting end of the united levers G.

I is the grooved wheels for chains to run in.

J is the fulcrum, and K in Fig. 2 shows the 45 swing end of the bridge resting on the projecting lever-head H.

L in Fig. 3 is a part of the timber of the swing, on the extreme end of which the bearer-iron M is attached, (shown in Fig. 3,) the iron bearing M just sliding onto the lever-head,

and also where it has come to its full bearing.

P is a roller attached to the lever-head H.

To meet the kind of bridges, whether solid abutments or open-timbered, the devices must be changed to different parts of the bridge, 55 but not changed in principle.

Fig. 1 shows its adaptation to solid approaches, and must all be on the outside and on each side precisely alike; but the levers on each side must extend and turn the corners, 60 uniting in the center of the approach and forming one center projecting head, lettered H. This produces a uniform and simultaneous movement of the gate.

In putting up a gate on an approach made 65 with open timber the machinery can all be put inside the same, duplicating the weights, wheels, and chains, as in solid abutments, to hold up the gate, and put anywhere best to operate on the gate; and the device for putting 70 down the gate by lever-power can be the same as in solid abutments; or, if desirable, one central lever of sufficient strength may be used, and also, if the gate can, according to circumstances, be set well back, a single lever and 75 only one wheel can be used. In this arrangement the end of the lever through the chain acts directly on the gate in pulling it down; but in all cases the end of the lever must form the projecting head H, in order that when the 80 swing comes to the iron bearer will ride on the top of the head H and pull the gate down.

Having thus described the different parts and their relations to each other, I will give a general idea of my invention.

It will be seen that to have a gate self-acting two things must be attained—first, to hold and keep a gate in place when the swing is swung, and consequently dangerous. This is obtained by the weights so arranged as is seen in specification and description given. The second thing to be attained is the getting the gate out of the way when the swing comes to place, so that it is not an obstruction to travel. Advantage is taken of the swinging of the bridge, giving a 95 free power and use for pulling the gate down just at the right time; and when the gate must be removed as the swing is coming to place, the iron bearer M strikes the lever-head H, the lever being pressed downward by the contact, 100

the other end of the lever flies up, and as the chain is fastened to the gate and the end of the lever the gate must come down. To attain this the length of lever and the length of chain, as 5 well as the situation of the fulcrum of the lever, must all be adjusted.

I therefore claim as my invention—

1. The combination, with the swing provided with the bar M, of the double lever G, 10 provided with the head H, and connections of the said lever with the rising and falling gate, substantially as described.

2. The combination, with the rising and falling gate, of the chains D, passing oppositely from the lower part of the said gate over the 15 sheaves I, arranged substantially as described; and at their ends connected respectively to the weight C and lever G, substantially as and for the purpose set forth.

HENRY MARCHETER.
